(57) **CLAIM**

I claim the ornamental design for a closure, as shown and described.

DESCRIPTION

FIG. 1 is a perspective view of a closure in accordance with the present invention.

FIG. 2 is a top plan view of the closure in FIG. 1, the bottom of the closure forming no part of the claimed design; and,

FIG. 3 is a side elevational view of the closure taken from the right in FIG. 2, the side elevational views from the top, left and bottom of FIG. 2 being identical to FIG. 3.
